LOUD SPEAKER

Filed May 1, 1924

10 INVENTOR.
Arthur Atwater Kent
BY Cornelius L. Elfreth
L. ATTORNEY

UNITED STATES PATENT OFFICE.

ARTHUR ATWATER KENT, OF ARDMORE, PENNSYLVANIA.

LOUD-SPEAKER.

Application filed May 1, 1924. Serial No. 710,240.

My invention relates to loud speakers, such as telephones provided with amplifying horns, utilizable in radio receiving apparatus and other relations.

5 In accordance with my invention, the instrument comprises a telephone housing which serves to join the instrument base, preferably of sheet metal, with the horn structure, which latter preferably comprises a 10 section of cast metal and a bell of sheet material, preferably metal, joined to the cast metal section.

More particularly in accordance with my invention, the telephone housing is provided 15 with external flange or lug structure, preferably intermediate the ends of the housing, to which the base is secured; and the telephone housing is provided with a neck having a sound passage registering with the 20 sound passage of the cast metal section of the horn, which is separate and distinct from the base and joins the neck of the telephone housing.

Further in accordance with my invention, 25 the cast section of the horn terminates at its large end in a flange to which the bell is attached, preferably by an inwardly extending flange registering with the flange upon the cast metal section.

30 My invention resides in structure of the character hereinafter described and claimed.

For an illustration of one of the various forms my invention may take, reference is to be had to the accompanying drawing, in 35 which:

Fig. 1 is a side elevational view, partly in section, of a loud speaker embodying my invention.

Fig. 2 is a fragmentary vertical sectional view, on enlarged scale, of the base, telephone housing and lower portion of the horn section.

Fig. 3 is a fragmentary horizontal sectional view, partly in plan, taken on the line 3—3 of Fig. 2.

Referring to the drawing, H is the telephone housing, preferably of cast metal, as a die casting, closed at one end by the member 1, integral with which is the neck 2 having the 50 sound passage 3 registering with the sound

passage 4 in the horn section S, preferably of cast metal, and provided at its lower end with the integral sleeve 5 which receives the neck 2, whereby the horn as a whole is supported directly and rotatable upon the telephone 55 housing H.

At its end opposite to the end closure 1 the housing H is open, and interiorly threaded to receive the exteriorly threaded cap C, or second housing member, preferably of molded 60 insulating material, within which is carried the telephone magnet system comprising the permanent magnet M having the pole pieces 6, 6, upon which are disposed the magnet coils 7, 7, whose terminals connect with the binding 65 posts 8, 8, with which connect the terminals 9, 9 of the flexible telephone cord 10 extending through the central aperture 11 in the cap C. Disposed in the upper end of the housing H is the telephone diaphragm T, controlled by the magnet system, and held between the resilient washers 12, 12 confined by the metal ring or washer 13 pressed upwardly by the undulating spring 14 engaging the upper or inner end of the cap C, which latter by 75 rotation with respect to the housing H advances or recedes, thereby adjusting the poles 6 with respect to the diaphragm T and adjusting the pressure exerted by the spring 14 upon the outer margin of the diaphragm T. 80

The telephone structure utilized may be of any suitable type or character, and the structure above described is merely an example of one of various forms which may be utilized.

Upon the exterior of the housing H, preferably between its upper and lower ends, is the outwardly extending lug structure or flange 15 having the ears 16, into which are threaded the screws 17 extending through holes in the upper inwardly extending flange 18 of the 90 hollow or bell-shaped base D, cheaply and simply formed of sheet metal and preferably having at its lower end the bead or roll 19, at which it rests upon a table or other support. At 20 the base D is provided with an aperture 95 through which the telephone cord 10 extends from the interior of the cap C to the binding posts of the circuit which supplies the sound- or speech-representing current.

At the upper and large end of the horn 100

section S it is provided with circumferentially spaced lugs or the circumferentially continuous flange 21, preferably inclined to the vertical, as indicated in Fig. 1. The bell 5 or second section B of the horn structure is constructed of sheet material, preferably metal, flaring from its small to its large end or mouth, where it is provided with the roll or bead 22. At its small end the bell B has 10 the inwardly turned lugs or circumferentially continuous flange 23 abutting against the lugs or flange 21 of the cast section S. Screws or equivalent means 24 secure the two sections S and B to each other at their abutting 15 lugs or flanges. As indicated, the screws 24 are preferably threaded through the lugs or flange 23 from the interior of the bell B into the lugs or flange 21 of the section S.

A horn comprising the sections S and B, of 20 the character and structure described, is simple, of low cost of manufacture, and yet fully effective for amplifying with small, if any, distortion the sound waves produced by the telephone diaphragm T.

25 By the combination of the character described there may be utilized for the base D sheet metal, as distinguished from more substantial cast metal bases, effecting substantial saving in cost, without sacrificing effectiveness. This is made possible by utilizing the telephone housing H as a connecting member between the base and the horn structure proper.

As indicated in the drawing, it is preferred 35 that the base D be secured to the under side of the flange or lug structure upon the housing H, though it will be understood that the flange 18 of the base D may be disposed above the flange or lug structure 15.

40 In the appended claims, when it is specified that an end of a horn or bell section comprises or terminates in "flange structure", it shall be understood that such term comprehends or includes flanges, ribs or the like.

45 What I claim is:

1. A horn for amplifying sound waves comprising a horn section of cast metal, outwardly extending flange structure at its larger end, a bell section of sheet metal, inwardly extending flange structure at its smaller end, said flange structures abutting each other in detachable relation, and means 50 for clamping the flange structures of said sections to each other.

55 2. A horn for amplifying sound waves comprising a gooseneck horn section of cast metal, external flange structure at its larger end, a bell section of sheet metal, inwardly extending flange structure at its smaller end, said 60 flange structures abutting each other in detachable relation, and means for clamping the flange structures of said sections to each other.
